UNITED STATES PATENT OFFICE.

EDMOND JANDRIER AND GEORGE SPENCER MERRILL, OF PEACE DALE, RHODE ISLAND.

EXPLOSIVE CHARGE.

1,109,292.

Specification of Letters Patent.

Patented Sept. 1, 1914.

Application filed March 7, 1910. Serial No. 547,736.

To all whom it may concern:

Be it known that we, EDMOND JANDRIER, a citizen of the French Republic, and GEORGE SPENCER MERRILL, a citizen of the 5 United States, both residing at Peace Dale, in the county of Washington and State of Rhode Island, (both having their post-office address at Peace Dale, Rhode Island), have invented certain new and useful Improvements in Explosive Charges, of which the 10 following is a specification.

Our invention relates generally to the charges of shells and other projectiles, or explosive carriers, such as mines and tor- 15 pedoes, which are to be disrupted by the contained charge, as distinguished from propulsive charges.

Heretofore projectiles, such as shells, have usually been charged with a high power explosive by pouring the explosive into the shell chamber in the shape of granular or crystalline powder, the size of the individual grains of which bear no specific relation to the size of the shell chamber. This opera- 20 tion is slow and tedious and not unaccom- 25 panied with danger, since high power explosives in this form are extremely sensitive, and some of the explosive, in the shape of fine dust, is unavoidably scattered and 30 gradually accumulates in the charging room, with consequent constant risk of explosion. It has also been proposed to charge shells with a high power explosive by first melt- 35 ing the explosive and pouring it in the melted state directly into the shell chamber. This, however, has proven undesirable not only because the melted charge adheres to the metal of the shell and is practically unremovable therefrom, but also because of 40 the unequal size of the crystals formed, by reason of the more rapid cooling of the exterior of the mass upon contact with the walls of the shell chamber, and because of 45 the danger incident to the possible adhe- 50 sion of some portion of the melted mass to the threaded part of the base of the shell. To the end of obviating these difficulties and 55 providing a charge of high explosive power which can be safely and conveniently placed 55 in the chamber of a shell or other explosive carrier we, in the first instance, take advan- 60 tage of the well known fact that certain high power explosives have relatively low melting points, below the temperatures at 65 which explosion thereof is likely to take place. In this class are some of the nitro

compounds such, for example, as trinitro cresol and trinitro toluol, which melt at 107° C. and 80° C., respectively.

While the melting point of picric acid, 122° C. is rather high and somewhat dan- 60 gerous, a mixture of picric acid and trinitro cresol in equal proportions melts at about 70° C. Hence in carrying our invention into effect we take any desired or suitable 65 high power explosive, or mixture of such explosives, having a safe low melting point, and, having melted it, pour the melted mass into molds of suitable shape and size where- 70 in it is allowed to slowly cool and harden. The molds may be of any size or shape re- 75 quired to produce charges, or sections, or parts of charges, of the desired size and form, which should be proportioned with reference to the particular use to which the 75 charge is to be applied, in the case of shells or similar projectiles, to the size of the cham- 80 ber which the charge is to occupy. Thus in forming charges for shells of a relatively small caliber the charge of which can con- 80 veniently be handled as a whole, we may cast the charge in a single piece of such size and shape as to entirely fill the shell cham- 85 ber, having such slightly lesser diameter than the shell chamber as to be readily in- 85 serted therein. Such a charge is indicated in the drawing, which shows a sectional view of a shell, A, with the contained charge, B.

The charge is preferably provided with a 90 central bore, C, formed in the process of casting, which may be utilized for the in- 95 sertion of a device to engage and remove the charge when desired, or for other purposes.

It is not necessary that the shell shall be 95 placed in a vertical position, as heretofore, for the purpose of charging, but it may be, and preferably is, charged with much greater convenience, in the same manner as a gun, while lying in a horizontal position. 100

An explosive in the form of cast units of considerable size is not readily explodable except by detonation; hence charges formed in this manner can be handled and shells can be charged therewith and the charges 105 withdrawn, if desired, with safety.

When it is considered that a fourteen inch shell, which can contain approximately but ninety-six pounds of a comminuted explosive, will contain about two hundred pounds 110 of such a charge as we have described, and that this charge is not only of far greater

efficiency per pound because of its greater density but that an increase in the mass of a confined explosive increases its explosive power in a ratio greater than its increase of weight, the importance of our invention in this connection will be realized.

After a shell has been loaded with its explosive charge, any usual or suitable detonating and firing means may be applied, 10 and the shell is then ready for use.

In carrying out our invention we preferably employ the process set forth in our companion application for Letters Patent of the United States, No. 547,738 filed of even 15 date with this application.

From the foregoing it will be seen that our invention provides an explosive charge of high efficiency, which can be handled and placed in a projectile with safety and safely 20 withdrawn if desired, and with which a projectile can, if desired, be charged immediately before being used, advantages which will be readily appreciated by those skilled in the art.

25 What we claim as new and desire to secure by Letters Patent is:

1. The combination with a projectile, provided with a charge cavity, of an explosive charge formed of an explosive material ca-

50 pable of being melted at a relatively low temperature, said charge comprising a cast body of said explosive in solid form and of such size and proportions as to closely but removably fit the charge cavity of said projectile, whereby the charge and the projectile can be safely and separately stored, transported, assembled, and separated, without disintegration of the charge.

2. The combination with a projectile provided with a charge cavity, of an explosive 40 charge, consisting of a cast body of high explosive material in solid homogeneous form containing the required quantity for a service charge for the projectile, and of a form and size to tightly but removably fit the 45 charge cavity thereof, said charge being provided with a longitudinal bore to facilitate the removal of the charge bodily and without disintegration, and to receive a detonator.

50 In testimony whereof, we have hereunto subscribed our names this 4th day of March, A. D., 1910.

EDMOND JANDRIER.
